COMBINED STORAGE AND CHARGING CASE FOR AN ELECTRIC SHAVER

William J. Rakocy, Clifton, N.J., assignor to Ronson
Corporation, Woodbridge, N.J.

Filed Mar. 26, 1970, Ser. No. 22,060

Term of patent 14 years

Int. Cl. D13—02

U.S. Cl. D26—15

Fig. 3.

Fig. 4.

Fig. 5.

Fig. 6.

FIG. 1 is a perspective view of a combined storage and charging case for an electric shaver showing my new design;

FIG. 2 is an exploded perspective view thereof;

FIG. 3 is a top plan view thereof;

FIG. 4 is a front elevation thereof;

FIG. 5 is a right end elevation thereof; and

FIG. 6 is a left end elevation thereof.

The broken line showing of the electric shaver is for illustrative purposes only.

I claim :

The ornamental design for a combined storage and charging case for an electric shaver, substantially as shown and described.
